JUG.

No. 20,062.

Patented July 29, 1890.

UNITED STATES PATENT OFFICE.

RICHARD WILLM. BINNS, OF WORCESTER, COUNTY OF WORCESTER,
ENGLAND.

DESIGN FOR A JUG.

SPECIFICATION forming part of Design No. 20,062, dated July 29, 1890.

Application filed April 21, 1890. Serial No. 348,919. Term of patent 7 years.

To all whom it may concern:

Be it known that I, RICHARD WILLIAM BINNS, director of the Royal Porcelain Works, Worcester, and a subject of the Queen of Great Britain, residing at Worcester, in the county of Worcester, in the Kingdom of Great Britain, have invented and produced a new and original Design for a Jug, of which the following is a specification, reference being had to the accompanying photograph, forming a part thereof.

The leading features of the design are as follows: a cylindrical or very slightly conical plain body, a bottom formed of a beading, an ornamentation resembling plaited work, a bulged-out part with ornamental fluting joining a bead at top and at bottom, and a handle clothed with foliage resembling an acanthus-leaf, the latter joining the body at the base.

The body of the jug is surmounted by a beading and ornamentation in relief resembling plaited work, slightly expanding upward for a short distance and then contracting, and the handle joins this contracted part by means of

a mass of foliage. The mouth is plain, cylindrical, or slightly conical, and the lip is formed of the face of a man with a seventeenth-century head-dress. 25

What I claim is—

The design for a jug herein shown and described, the same comprising an ornamental bulged and beaded and columned bottom, a plain and nearly cylindrical body, an ornamented, beaded, and slightly-projecting band bulged in the center and narrowed considerably above the middle, a narrower cylindrical mouth, with a lip formed of the face of a mask, and the handle an ordinary handle covered with foliage. 30 35

In testimony whereof I have signed my name to this specification in the presence of two subscribing witnesses.

RICHD. WILLM. BINNS.
